UNITED STATES PATENT OFFICE.

JAMES FRASER, OF HILLCREST, DELAWARE, ASSIGNOR TO THE SPEAKMAN COMPANY,
OF WILMINGTON, DELAWARE, A CORPORATION OF DELAWARE.

DESIGN FOR A VALVE HANDLE.

Application filed October 15, 1928. Serial No. 28,502. Term of patent 7 years.

To all whom it may concern:

Be it known that I, JAMES FRASER, a citizen of the United States, residing at Hillcrest, Edgemoor, in the county of Newcastle and State of Delaware, have invented a new, original, and ornamental Design for a Valve Handle, of which the following is a specification, reference being had to the accompanying drawing, forming part thereof.

Fig. 1 is an elevation, and Fig. 2 is a plan view of a valve handle showing my new design.

I claim:

The ornamental design for a valve handle, substantially as shown.

JAMES FRASER.
